Primary Examiner — Cynthia Ramirez(74) *Attorney, Agent, or Firm* — Procopio, Cory, Hargreaves & Savitch LLP(57) **CLAIM**

The ornamental design for a lid locking apparatus, as shown and described.

DESCRIPTION

FIG. 1 is a perspective view of the lid locking apparatus shown in an open position.

FIG. 2 is another perspective view of the lid locking apparatus shown in an open position and is shown with a chain and padlock attached.

FIG. 3 is a further perspective view of the lid locking apparatus and is shown in almost closed position with a chain and padlock attached; and,

FIG. 4 is a still further view of the lid locking apparatus and is shown in a closed position with a chain and padlock attached.

The broken lines showing a chain and lock in FIGS. 2, 3 and 4 show environment and form no part of the claimed design.

1 Claim, 2 Drawing Sheets(56)
